(57) CLAIM

The ornamental design for a portable telephone, as shown and described.

DESCRIPTION

FIG. 1 is a front view of a portable telephone showing my new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof;

FIG. 7 is a front view of operation portion thereof shown separate from the liquid crystal display portion thereof for convenience of illustration;

FIG. 8 is a rear view of side with liquid crystal display portion thereof shown separate from the operation portion thereof for convenience of illustration;

FIG. 9 is a front view with the display rotated thereof;

FIG. 10 is a rear view with the display rotated thereof;

FIG. 11 is a left side view with the display rotated thereof;

FIG. 12 is a right side view with the display rotated thereof;

FIG. 13 is a top plan view with the display rotated thereof;

FIG. 14 is a bottom plan view with the display rotated thereof;

FIG. 15 is a front view with the liquid crystal display rotated into the horizontal direction thereof;

FIG. 16 is a perspective view with the display rotated thereof;

FIG. 17 is a central longitudinal end view with the display rotated and internal structure omitted thereof;

FIG. 18 is an enlarged view of portion A—A in FIG. 17;

FIG. 19 is an enlarged view of portion B—B in FIG. 17; and,

FIG. 20 is an enlarged view of portion C—C in FIG. 17.
